INTERCHANGEABLE HEAD, RATCHET TYPE
SOCKET WRENCH

Lester O. Wilson, Los Angeles, Calif.

Application July 29, 1941, Serial No. 404,445

4 Claims. (Cl. 81—58)

This invention pertains to a ratchet type wrench provided with interchangeable heads, the wrench being thus adapted for use on nuts and bolts differing in polygonal cross section, size, etc. In its preferred form, the wrench of this invention is of the ratchet type so that the nut or bolt may be tightened or loosened by a repeated oscillating or rocking movement of the handle of the wrench. Moreover, the wrench may be provided with a handle which is movably and angularly connected to the wrench, thereby permitting the wrench to be used in those positions which do not accommodate a rigid or fixed handle.

Generally stated, the wrench of the present invention comprises a body member adapted to receive interchangeable heads, the heads having sockets formed therein, the sockets differing in size and cross section so as to permit the wrench to be used on various types and sizes of nuts. The body member of the wrench is provided with an annular ratchet lying in a plane transverse to the axis of the socket in the interchangeable head. The interchangeable heads are also provided with annular ratchet rings adapted to engage the ratchets on the body member. Means are also provided in the body member for releasably retaining the head against the fixed ratchet of the body member. The body member may then be connected in any suitable manner to a handle, such connection being preferably of the angularly adjustable ratchet type so as to facilitate insertion and use of the wrench in narrow or angularly disposed positions.

An object of the present invention, therefore, is to disclose and provide a simple, strong, relatively lightweight and positive type of interchangeable head wrench.

A further object of the invention is to disclose and provide an interchangeable head, ratchet type socket wrench adapted for use with an angularly adjustable handle.

These and other objects and advantages of the invention will become apparent to those skilled in the art from the following detailed description of an exemplary form of the invention, reference being had to the appended drawing, in which:

Fig. 1 is a perspective view of a wrench embodying the present invention, the wrench illustrated including an angularly adjustable handle.

Fig. 2 is a perspective view of an interchangeable head element and shows the bottom or ratchet surface of such head.

Fig. 3 is a vertical section through the wrench. As shown in the drawing, the wrench includes a body member generally indicated at 10 adapted to receive the interchangeable heads 11. These heads 11 snugly but rotatably fit into a bore 12 formed in the body member, the end of the bore being partly closed by means of an inwardly extending circular lip 13 which may be integral with the body portion 10. The inner transverse surface of the lip 13 is provided with a plurality of ratchet teeth 14. The lower end 15 of the removable head 11 is also provided with an annular ring of ratchet teeth 16 adapted to engage and cooperate with the ratchet teeth 14. The head 11 is shown provided with an axially disposed socket 17 having a polygonal section corresponding in size to the nut or bolt head with which such head is designed to be used. For example, the socket 17 may be square, hexagonal, octagonal or twelve-sided (as shown) in cross section.

The head 11 is also provided with a seating groove formed in the outer cylindrical surface of the head, such groove being generally indicated at 18, said groove having one virtually transverse side 19 adjacent the end 15 of the head 11.

The body member 10 may be connected to a handle 20 or it may be integral with such handle. Preferably, however, the handle 20 is attached to the body member 10 by means of a universal or angularly adjustable joint or connection such as is generally indicated at 21. Details of this joint or connection need not be shown since such connections or joints are well known.

In the body member 10 adjacent the handle 20 or the connection 21 spring actuated means are provided for releasably holding the head 11 within the bore 12 of the body member 10. As more specifically shown in Fig. 3 the body portion 10 may be provided with an angularly disposed bore 22 directed inwardly and downwardly toward the inner surface of the lip 13, said bore being adapted to slidably receive a pin 23 provided with a blunt end adapted to rest against the transverse side 19 of the groove 18 in the head 11. The bore 22 may merge into an enlarged bore portion 24 adapted to threadedly receive a stop 25 and a spring 26 which bears thereagainst and against a stop carried by the pin 23 so as to yieldably urge said pin against the side 19 of the head 11.

The body member 10 adjacent the upper end 55 of the enlarged bore 24 may be provided with

a slight boss 28 adapted to protect the head of the pin 23 against accidental breakage.

It will be evident that various heads 11 may be inserted into the body member 10 of the wrench by pulling the pin 23 so as to withdraw it into the bore 22, inserting the head 11 and then releasing the pin 23. The spring actuated pin bears against the side 19 of the removable head 11 and causes the ratchet teeth 14 and 16 to engage. Since the ratchet teeth are arranged around the periphery of the head 11 and in a plane transverse to the axis of the socket 17, a large gripping area functions at all times so that all necessary force may be exerted by the handle 20 of the wrench in tightening nuts with the socket wrench. The pin 23 gives somewhat when the handle is oscillated, however, so that the ratchet action may be employed in actually using the wrench. It is also to be noted that the pin 23 bears downwardly toward the inwardly extending lip 13 of the body member, thereby further assuring intimate and positive contact of the ratchet teeth 14 and 16. Again it is to be noted that the spring actuated, selectively releasable pin does not extend into the handle 20 and does not interfere with the angularly adjustable joint or connection between the body member 10 and the handle 20.

The twelve-sided socket 17 illustrated may be used on square or hexagonal nuts and may also be used to receive and hold an extension bar carrying a socket wrench on its end, such arrangement permitting the use of the device in difficultly accessible positions.

Although an angularly adjustable handle has been shown, it is to be understood that handles integral with the body member may also be employed. Moreover, body members 10 may be attached to or formed as a part of both ends of a handle, thereby giving rise to double-ended wrenches.

I claim:

1. In an interchangeable head, ratchet type wrench, the combination of: a body member provided with a cylindrical bore therethrough adapted to receive a socket head; a circular lip extending inwardly at one end of said bore and a plurality of ratchet teeth formed in the inner transverse face of said lip; a cylindrical socket head having an axially disposed socket, ratchet teeth in one end of said head and a seating groove formed in the outer surface of the head, said groove having one virtually transverse side adjacent the end of the head and a spring actuated pin angularly disposed in the body member adjacent said head receiving bore and adapted to extend into the groove formed in the head and press against the side of said groove to hold a socket head in said body member.

2. In an interchangeable head, ratchet type

wrench, the combination of: a body member provided with a cylindrical bore therethrough adapted to receive a socket head; a circular lip extending inwardly at one end of said bore and a plurality of ratchet teeth formed in the inner transverse face of said lip; a cylindrical socket head having an axially disposed socket, ratchet teeth in one end of said head and a seating groove formed in the outer surface of the head, said groove having one virtually transverse side adjacent the end of the head and a bore in the body member angularly directed inwardly toward the inner face of said lip, and a spring-actuated releasable pin movably held in said bore and adapted to extend into the groove formed in the head to press against the side of said groove to hold the head in said body member.

3. In an interchangeable head, ratchet type wrench, the combination of: a body member provided with a cylindrical bore therethrough adapted to receive a socket head; a circular lip integral with the body member and extending inwardly at one end of said bore and a plurality of ratchet teeth formed in the inner transverse face of said lip; a cylindrical socket head having an axially disposed socket, ratchet teeth in one end of said head and a seating groove formed in the outer surface of the head, said groove having one virtually transverse side adjacent the end of the head and a bore in the body member directed angularly, downwardly and inwardly toward the inner face of said lip, a spring actuated releasable pin movably held in said bore and adapted to extend into the groove formed in the head to press against the side of said groove to hold the head in said body member, and handle means attached to said body member.

4. In an interchangeable head, ratchet type wrench, the combination of: a body member provided with a cylindrical bore therethrough adapted to receive a socket head; a circular lip integral with the body member and extending inwardly at one end of said bore, and a plurality of ratchet teeth formed in the inner transverse face of said lip; a cylindrical socket head having an axially disposed socket, ratchet teeth in one end of said head, and a seating groove formed in the outer surface of the head; a bore in the body member directed angularly, downwardly and inwardly toward the inner face of said lip, and a spring-actuated releasable pin movably held in said bore and adapted to extend into the seating groove to hold the head in said body member, the said pin being provided with a head extending above the surface of the body portion adjacent the cylindrical bore whereby the pin may be manually released to permit removal of the socket head from the body member.
